(57) **CLAIM**

I claim the ornamental design for the portable feedback station, as shown and described.

DESCRIPTION

FIG. 1 is a front perspective view of a portable feedback station embodying my design;

FIG. 2 is a front elevational view of the portable feedback station as shown in FIG. 1;

FIG. 3 is a rear elevation of the portable feedback station as shown in FIG. 1;

FIG. 4 is a top plan view of the portable feedback station as shown in FIG. 1, the bottom view is a flat oval; and,

FIG. 5 is a right side elevational view of the portable feedback station as shown in FIG. 1, the left side view being a mirror image.

The broken lines show the stand on which the portable feedback station is situated and forms no part of the design to be patented.
